UNITED STATES PATENT OFFICE.

HENRI DOLTER, OF PARIS, FRANCE.

APPARATUS FOR ELECTRIC TRACTION.

SPECIFICATION forming part of Letters Patent No. 662,921, dated December 4, 1900.

Application filed July 6, 1899. Serial No. 722,913. (No model.)

To all whom it may concern:

Be it known that I, HENRI DOLTER, engineer, a citizen of the Republic of France, residing at No. 41 Rue Taitbout, Paris, France, have invented certain new and useful Improvements in Apparatus for Electric Traction, of which the following is a specification.

My invention has relation to a new mode of supplying, in underground conduits, current for electric traction. This system is characterized principally by the four following arrangements: first, a series of similar contacts each formed of two magnetic parts separated by a non-magnetic piece; second, a balanced contact supported by magnetic pieces, which permits of arc ruptures of any required length being obtained; third, a special means for connecting with the underground conductor at each contact, and, fourth, a suspended brush beneath the vehicle, consisting of two flexible longitudinal bars provided with cross-pieces and electromagnets, which induce in each of these bars a different polarity, each bar touching one of the two magnetic parts in such a manner as to close the magnetic circuit through the soft iron of the balance, and this with a minimum of gap.

My invention, stated in general terms, consists of an apparatus for electric traction when constructed and arranged in substantially the manner hereinafter described and claimed.

My invention is represented in the accompanying drawings, in which—

Figure 1 is a section on the center of a contact, taken perpendicularly to the track. Fig. 2 is a section at right angles to the preceding, and consequently parallel to the rails. Fig. 3 is a diagram showing the path of current in the electric circuit. Fig. 4 is an enlarged detail sectional view of certain parts illustrated in Fig. 2, and Fig. 5 is an enlarged rear elevational and sectional view of certain parts illustrated in Fig. 1.

Referring to the drawings, A A' are the two magnetic parts, each semicircular, as shown; but they may be of any other shape.

B is the non-magnetic piece separating parts A and A'. Beneath these parts A and A' is fixed, by means of a screw or otherwise, a cylindrical box C, of porcelain or other insulating material. Between the parts A A' and the box C is placed an elastic washer D,

of leather, lead, or other substance, to make a tight joint. The bottom of the box C is centrally pierced with a hole and is provided with concentric rings c, as in bell-insulators. Beneath the parts A and A' is a carbon support E, on which the balance F oscillates. The long arm of the balance is bent and is provided at the bottom with a highly-conducting carbon bob f. This long arm consists of a crystal tube f', inside of which is a fusible wire f'' and tale or insulating powder. One end of the short arm carries a cylinder G, of soft iron, which when attracted by the magnetic parts A and A' lodges in a cavity formed in these parts, as is illustrated in Fig. 2. The two trunnions f³ of the balance F, which enter holes in the support E, are also of carbon. In the box C is arranged a suitably-bent conductor H, provided with a threaded end h, passing through the hole at the bottom of the box C. Upon the thread h is secured a screw-cap I, separated from the bottom of the box C by means of an elastic washer i, so as to make a joint. At the other end of the conductor H a carbon block J is located, having a cavity in which the bob f lodges. The bottom of the box is coated with a layer K of resin or other analogous material. The parts A A' are pierced with holes for receiving screws for fixing the box C to the parts A A', and these parts and box are supported upon a non-magnetic ring L, which is embedded in the asphalt or concrete cylinder M. This cylinder is supported on a cement tube m, and the tube m is provided with a lateral slot m' for the passage of a wire o to an electric main P by means of a junction-box p, containing a fuse, and the other end 90 of the derived circuit O is provided with a cap Q, forming a bell-insulator of ebonite or other insulating material. This cap has upon it rings q q, entering the rings c of the box C, as illustrated in Figs. 1 and 2.

R is a double union soldered on the derived circuit and screwing onto the piece I.

Care should be taken to coat the recesses in the bell-insulator with vaseline or a solid grease.

Under the vehicle to be propelled is suspended a brush insulated from the vehicle. This brush is composed of two iron bars T T', connected together by cross-pieces t, upon

which an insulated copper wire is wound to form an electromagnet U. One end of the insulated copper wire of the electromagnets is connected to one of the two bars T or T'—5 in the drawings the bar T'—and the other end to the terminals of the regulators corresponding to those of the trolley of an aerial line, (designated by 3 on the drawings.)

It is best to explain the action of the system with reference to Fig. 3, in which the same letters designate the like parts as in Figs. 1 and 2. N and S indicate, respectively, north and south polarities. In order to explain the action of the system, I make 15 mention of certain parts and arrangements forming no part of this invention and which are designated by the figures in the description. A vehicle equipped to be propelled on the trolley system carries brushes T T' and 20 a small battery of accumulators 1, the positive pole of which is connected to one of the bars of the brush and the negative to a contact 2 of the regulator in such manner that the battery 1 is in circuit with the electromagnets U by short-circuiting the contact 2 with the contact 3 only when the vehicle is 25 in motion and is thrown out of circuit when it is desired to stop the vehicle or to put on the brake by transforming the motors 4 into 30 the generators. The contact 3 corresponds to the terminals of the regulators of the trolley of an aerial line. The number of elements is calculated in such a manner as to obtain in the winding of the electromagnets 35 exciting the bars T T' a number of ampere-turns sufficient to attract the armature G at any speed. The resistance of the winding is also calculated in such manner that in daily work the power absorbed by the battery is in 40 excess of that required to be given out, so that no thought need be taken to always have an excess. This arrangement also allows a very small difference of potential to be maintained between the bars and the 45 other end of the exciting-wire. At both ends of the vehicle are two metallic brushes 5, electrically connected to the wheels in such manner as to short-circuit the pieces A A' of the box C when the part G does not fall 50 back. This short-circuiting causes fusion of the wire f² in the tube f', the rupture of the crystal cylinder F thereby breaking the derived circuit. The return of the current to the generator takes place by the rail 6. The 55 vehicle is lighted by two sets of lamps, the one, 7, in series with the main circuit, and the other, 8, in parallel with the battery 1. When, therefore, the vehicle equipped as described is placed on a track having the magnetic contacts A A', arranged at suitable distances apart, less than the length of the bars placed beneath the vehicle, and one of the handles of one of the regulators is turned, the ac-

cumulators 1 are placed in series with the windings U, and the two bars T T' each acquire throughout their length a different polarity, T being of north polarity and T' of south, and communicate such excitation to the two pieces A A', which attract the armature G, as illustrated in dotted lines in Fig. 2. 65 The bob f becomes lodged in the cavity of the block J, the pressure on these two parts being regulated by the distance between the armature G and the parts A A' of the box C. At this moment the current is closed to the 70 motors 4 and these are put into action. The bars T T' are soon brought by the motion of the vehicle to the next metallic contact, at which the same operation of closing the metallic circuit takes place. As the vehicle advances the bars leave the preceding metallic contact, the soft-iron piece G of which is no longer attracted by the pieces A A', falls, causing the bob F to assume a vertical position, such as illustrated in full lines in Figs. 80 75 and 4. The contact is therefore again insulated from the electric main. If from any cause the piece G does not fall, the brush 85 will close a short circuit through the contact which will cause the fusible wire to fuse, the 90 rupture of the tube f', and the fall of the bob f. The length of the long arm or glass tube f' is calculated in such a manner as to obtain a rupture sufficient to insure that there will be no arc no matter what the quantity 95 and tension of the current may be.

Of course as to details of construction and the arrangement of the apparatus hereinbefore explained modifications may be made, and hence I do not wish to limit myself to 100 any particular form or shape of contact.

Having thus described the nature and objects of my invention, what I claim as new, and desire to secure by Letters Patent, is—

In a system of electric traction, a source of 105 electric energy, a conduit wherein the source is located, a box of insulating substance located in said conduit, two magnetic contact-pieces supporting said box, a non-magnetic piece separating the magnetic pieces from 110 each other, a conductor located in the insulating-box and normally in electric connection with the source of energy, and a pendulum adapted to be elevated when the magnetic pieces are magnetized to thereby complete 115 the circuit from the conductor through said magnetic pieces, substantially as and for the purposes described.

In testimony whereof I have signed this specification in the presence of two subscribers 120 and witnesses.

HENRI DOLTER.
